COVER FOR AN AEROSOL DISPENSER

Robert L. Weber III, New Canaan, Conn., assignor to
Time-Mist Inc., Stamford, Conn., a corporation of Delaware

Filed Sept. 30, 1965, Ser. No. 87,249

Term of patent 14 years

(Cl. D58—26)

Fig. 1

Fig. 2

Fig. 4

FIG. 1 is a front perspective view of a cover for an aerosol dispenser showing the new design, with an aerosol can shown fragmentarily in broken lines for illustrative purposes only;

FIG. 2 is a fragmentary right side elevational view; FIG. 3 is a fragmentary left side elevational view; and FIG. 4 is a fragmentary transverse sectional view.

I claim:

The ornamental design for a cover for an aerosol dispenser, substantially as shown and described.
